Primary Examiner — Randall Gholson*(74) Attorney, Agent, or Firm* — Oliff PLC**CLAIM**

The ornamental design for a stator for a ventilator or blower, as shown and described.

DESCRIPTION

FIG. 1 is a front view of a stator for a ventilator or blower. FIG. 2 is a right side view of the stator for a ventilator or blower.

FIG. 3 is a top view of the stator for a ventilator or blower. FIG. 4 is a bottom view of the stator for a ventilator or blower. FIG. 5 is a rear view of the stator for a ventilator or blower; and,

FIG. 6 is a rear perspective view of the stator for a ventilator or blower.

The broken lines depict environmental subject matter only and form no part of the claimed design.
